GARMENT FINISHING APPARATUS

Frank G. Hoover and Harry E. McCollaugh, Escondido, and Charles H. Free, Pasadena, Calif.

Application March 4, 1955, Serial No. 492,074

3 Claims. (Cl. 223—73)

The present invention relates generally to dry cleaning of garments and more particularly to a garment finishing apparatus.

The primary object of this invention is to provide a garment finishing apparatus on which garments can be processed in the upright position in which they are normally worn, this being the ideal or optimum position since the finished garments then retain their correct shape or, if the garments have become misshapen, the use of the instant apparatus tends to correct this by blocking the garments back into form. An ancillary object is to provide a machine which will finish garments such as trousers and skirts so that they will hang straight.

Another object of this invention is to provide a garment finishing apparatus in which the supporting stand also serves as the main supply conduit for steam and hot air used in the process.

Another object of this invention is to provide a finisher upon which it is extremely easy to place garments in position for processing, thus saving time and labor.

Another object of this invention is to provide a garment finishing apparatus which is particularly suitable for garments such as trousers and skirts and which has an adjustable waist portion to accommodate many sizes of garments.

Another object of this invention is to provide a finisher with a waist portion having means for gentle expansion thus preventing shrinkage of the garment during processing.

Another object of this invention is to provide a garment finishing apparatus having easily operated pleat pressers mounted thereon.

Another object of this invention is to provide a garment finishing apparatus having spring clips for initially retaining a garment, thus leaving the operator's hands free for zipping, buttoning and adjusting the garment.

Another object of this invention is to provide a garment finishing apparatus having means for preventing the accumulation of condensation therein which would otherwise adversely affect the drying stage of the process.

Finally it is an object to provide a garment finishing apparatus of the aforementioned character which is simple, safe and generally convenient to operate, and which will give generally efficient and durable service.

With these and other objects definitely in view, this invention consists in the novel construction, combination and arrangement of elements and portions, as will be hereinafter fully described in the specification, particularly pointed out in the claims, and illustrated in the drawings which form a material part of this disclosure and wherein similar characters of reference indicate similar or identical elements and portions throughout the specification and throughout the views of the drawings, and in which:

Fig. 1 is a side elevation view of the apparatus.

Fig. 2 is a front elevation view thereof.

Fig. 3 is a top plan view thereof with the pleat pressers in position.

2

Fig. 4 is an enlarged fragmentary sectional view taken on the line 4—4 of Fig. 2.

Fig. 5 is an enlarged sectional view taken on the line 5—5 of Fig. 2.

Fig. 6 is an enlarged fragmentary sectional view taken on the line 6—6 of Fig. 2.

Fig. 7 is an enlarged fragmentary sectional view taken on the line 7—7 of Fig. 3.

Fig. 8 is a fragmentary front elevation view of the structure shown in Fig. 7.

Fig. 9 is an enlarged fragmentary sectional view taken on the line 9—9 of Fig. 8.

Fig. 10 is an enlarged fragmentary sectional view taken on the line 10—10 of Fig. 1.

Referring now to the structural features as shown in the drawings, the apparatus comprises a base 10 on which is mounted a hollow, upright pillar 12 having a forwardly extending top portion 14 at the upper end thereof, said top portion including a downwardly turned forward end 16. Fixed to and suspended beneath the end 16 is the garment holder assembly 18 comprising a fixed plate 20 on which are mounted opposed side forms 22. These side forms 22 are externally arcuate in horizontal cross section and are mounted for sliding movement, as hereinafter described more fully, toward and away from the fixed plate 20. Extending downwardly from the fixed plate 20 are leg elements 24 which conduct steam and hot air to garment portions, such as the legs of trousers, being processed.

The base 10 is a hollow casing of suitable construction and contains a blower 26 together with the necessary piping, valves and related equipment used in conventional garment finishing machines. The arrangement and function of the steam and air supply equipment is well known to those versed in the art and need not be described in detail, the present invention being primarily concerned with and related to the upright disposition and as well as the particular structure of the garment holder assembly. Extending from the base 10 are foot control pedals 28 and 30 for control of steam and air, respectively. The pillar 12 as shown is rectangular in cross section and may be constructed of sheet material welded together, although preformed pipe of any suitable cross section may also be used.

The fixed plate 20 has a central opening 32 corresponding to the opening of the end 16, so that steam or air from the pillar 12 can pass directly into the garment holder. Each side form 22 comprises a generally semi-circular plate 34 having a pair of spaced, parallel guide bars 36 integral therewith and extending from the flat or inner side thereof. The guide bars 36 straddle the opening 32 and are slidably retained in guide rails 38 fixed beneath the fixed plate 20, so that the side forms are laterally slidable on said fixed plate. Movement of the side forms 22 is accomplished by a fluid operated cylinder 40, or the like, having actuating rods 42 which are connected to the plates 34 by brackets as in Fig. 4. Secured to the arcuate edge of each plate 34 is a downwardly extending form panel 46 tapering toward the lower end thereof. The form panels 46 are of perforated sheet material as shown, or may be made from expanded metal lath for simplicity, said form panels being exteriorly covered by a cloth pad 48, or the like, tied or otherwise secured thereto. It should be understood that means other than a fluid operated cylinder may be used to control the movement of the side forms 22.

Fixed to the upper surface of each plate 34 adjacent its outer edge is an upright post 50 to which is attached a spring clip 52. The spring clip 52 is intermediately pivoted on a bolt 54 while the upper end is held on an adjustment screw 56 said spring clip being biased outwardly by a compression spring 58, as shown in Fig. 10.

The lower end 60 of each clip 52 is arcuately formed to present a smooth contact surface which is held tightly against the pad 48.

Each side form 22 is also fitted with a pleat presser 62 comprising a presser panel 64 tapered toward its lower end and arcuately shaped to fit closely against the surface of the padded form panel 46. The presser panel 64 is made from perforated sheet material or expanded metal lath and is covered by a pad 66. The presser panel 64 is reinforced by a longitudinal spine 68 and is mounted on a toggle 70 of conventional design. This toggle 70 comprises an actuating handle 72 pivotally mounted on a bracket 74 and a pressure bar 76 also pivotally attached to said bracket. The actuating handle 72 and pressure bar 76 are coupled by a toggle link 78, the structure and function of such a mechanism being well known to those versed in the art. The pressure bar 76 extends longitudinally with the presser panel 64 and is terminally secured to the spine 68 by a bolt 80 on which is a spring 82 to bias said pressure bar away from the presser panel as shown in Figs. 7-9. Adjacent the upper end of the presser panel 64 is fixed a yoke 84 which straddles the pressure bar 76, a screw 86 being inserted through said yoke and bearing against the pressure bar to adjust the alignment of the presser panel relative thereto. The bracket 74 has a tubular portion 88 which fits over an upstanding post 90 fixed to the upper surface of the plate 34.

The leg elements 24 each comprise a downwardly extending heating pipe 92 at the lower end of which is a moisture trap 94, while extending upwardly from the trap is a return pipe 96. Steam is circulated through the heating pipe 92 and back through the return pipe 96 from a supply pipe 98 and through a condenser 100. The heating pipe 92 is enclosed in a perforated jacket 102 which is sealed thereto at both ends. Within the jacket 102 is a perforated steam delivery pipe 104 having a closed lower end. The jacket 102 is enclosed by a cover 106 of suitable material which allows passage of the steam therethrough while preventing the issuance of direct jets from the perforations, as shown in Fig. 6.

The leg elements 24 are enclosed in an outer bag 108 having bifurcated leg portions 110. This bag 108 is shaped in the general manner of a pair of trousers and the upper end or waist portion thereof is attached to the plate 20 and plates 34 by tying or other suitable methods. The bag 108 has a certain amount of fullness to allow for expansion and contraction of the side forms 22 and is made of semi-impervious material which allows slow leakage of steam or air therefrom.

Movement of the side forms 22 is governed by arcuate control of the air supply to the cylinder 40. The air supply hoses 110 to this cylinder 40 are connected to a control unit 112 having foot pedals 114 and 116, one of said pedals controlling expansion and the other controlling retraction. The air supply to the control unit 112 passes through a regulator valve 118 by which the air flow can be accurately controlled. It is feasible that the regulator valve 118 may be calibrated to indicate the exact setting necessary to expand the side forms 22 to fit the specific waist size of a garment. The control unit 112, of course, contains conventional valves operated by the foot pedals 114 and 116, the structure and function of such mechanisms being well known.

To prevent soiling of garments on the lower parts of the apparatus, a forwardly and laterally extending guard 120 is secured to the pillar 12 slightly above the base 10. This guard 120 may be made of wire mesh or expanded metal lath and is fitted with a peripheral bumper strip 122 of rubber, plastic, or the like.

The operation of the device is as follows:

The garment to be finished, such as a pair of trousers, is lifted upwardly over the garment holder assembly 18 so that the leg elements 24 enter the legs of the trousers. The waist band portion of the trousers are inserted under

the clips 52, as indicated at 124 in Fig. 10, so that the trousers are held in place. The operator's hands are thus free to adjust and fasten the trousers in place correctly for finishing. The side forms 22 are retracted initially to facilitate placement of the trousers and are expanded, after the waistband is fastened, by means of the foot pedal 114. The regulator valve 118 is, of course, adjusted so that the expansion of the side forms 22 is sufficient to hold the waist band of the trousers under tension without strain. It should be noted that in the upright position the trousers hang in the natural position as worn, thus all creases and folds appear exactly as required in the finished garment. It has been found that this vertical position enables the operator to process the garment more efficiently and neatly than is possible with the horizontal type machines normally used. When the trousers are in place the steam is turned on and issues from the delivery pipes 104 into the jackets 102, the steam then passing through the covers 106 into the bag 108. Steam is also supplied through the pillar 12 itself, which is a hollow conduit as well as a support for the apparatus, the steam entering the bag 108 through the opening 32 in the plate 20. The bag 108 is thus filled with steam and becomes inflated to fill the trousers out to their full shape, the steam then gradually penetrating the bag 108 and softening the material of the trousers, so that wrinkles are removed under the tension caused by the expanded bag. When the processing is satisfactorily completed, the operator turns off the steam and turns on the hot air which quickly dries the garment, still in the expanded position.

The pleats usually incorporated into the upper frontal portion of trousers are neatly finished by means of the pleat presses 62. When the pleats have been adjusted by the operator, the pleat presses 62 are swung down and locked in place by the toggles 70, so clamping the pleated portion of the trousers firmly against the padded form panels 46. Steam is then applied to set the pleats, the steam passing through the form panels 46 and the presser panels 64, both of which are perforated for that purpose. Hot air is next applied to complete the pleating process.

A minor problem with the vertical type of garment finishing machine is the accumulation of condensation in the lower portions of the apparatus and the consequent permanent dampness. This has been avoided in the leg elements 24 by passing steam continuously through the imperforate heating pipes 92 so that the interior of each jacket 102 is constantly heated. The steam from the delivery pipes 104 is thus maintained at vaporization temperature and does not condense in the bottom of the jackets 102. A small amount of condensation in the heating pipes 92 is unavoidable and this condensate is retained in the traps 94. These traps, however, are in a closed circuit and the condensate is not open to the interior of the bag 108, so that the humidity therein is unaffected.

After the finishing operation is completed, the pleat presses 62 are raised and the side forms 22 are retracted slightly to facilitate removal of the garment, the guard 120 preventing the garment from being soiled on the floor as it is lowered from the holder assembly 18.

The operation of this invention will be clearly comprehended from a consideration of the foregoing description of the mechanical details thereof, taken in connection with the drawings and the above recited objects. It will be obvious that all said objects are amply achieved by this invention.

Further description would appear to be unnecessary. It is understood that minor variation from the forms of the invention disclosed herein may be made without departure from the spirit and scope of the invention, and that the specification and drawings are to be considered as merely illustrative rather than limiting.

We claim:

1. A garment finishing apparatus comprising: a base; an upright hollow pillar fixed on said base; said pillar having a laterally extending upper portion; a garment holder assembly suspended from said portion; said holder assembly including a fixed plate mounted on said portion; guide rails secured beneath said fixed plate normal to said upper portion; a pair of side plates having spaced extended guide bars slidably engageable in said rails; a downwardly extending, rigid side form panel fixed to each of said side plates; said side form panels being perforated and shaped to engage in the waistband portion of a garment; porous covers secured to said form panels; and means for laterally adjusting the spacing of said form panels; spring clips mounted on each of said side plates and extending downwardly over said form panels to engage and retain a garment thereon; a rigid pleat presser pivotally mounted on each of said side plates to swing downwardly against the surfaces of said side form panels; said pleat presses being perforated and shaped to fit closely the surface of said form panels; and porous covers secured on said pleat presses; a toggle mechanism operatively connected to said pleat presses to lock the same in place against said form panels; a pair of downwardly extending leg elements secured to said fixed plate; and means for conducting fluids through said leg elements.

2. A garment finishing apparatus comprising: a base; an upright hollow pillar fixed on said base; said pillar having a laterally extending upper portion; a garment holder assembly suspended from said portion; said holder assembly including a fixed plate mounted on said portion; guide rails secured beneath said fixed plate normal to said upper portion; a pair of side plates having spaced extended guide bars slidably engageable in said rails; a downwardly extending, rigid side form panel fixed to each of said side plates; said side form panels being perforated and shaped to engage in the waistband portion of a garment; porous covers secured to said form panels; and means for laterally adjusting the spacing of said form panels; spring clips mounted on each of said side plates and extending downwardly over said form panels to engage and retain a garment thereon; a rigid pleat presser pivotally mounted on each of said side plates to swing downwardly against the surfaces of said side form panels; said pleat presses being perforated and shaped to fit closely the surface of said form panels; and porous covers secured on said pleat presses; a toggle mechanism

operatively connected to said pleat presses to lock the same in place against said form panels; a pair of downwardly extending leg elements secured to said fixed plate; said leg elements each comprising an imperforate fluid conducting pipe; a perforated fluid delivery pipe generally parallel thereto; a perforated jacket enclosing said conducting pipe and said delivery pipe; and a porous cover surrounding said jacket.

3. A garment finishing apparatus comprising: a base; an upright hollow pillar fixed on said base; said pillar having a laterally extending upper portion; a garment holder assembly suspended from said portion; said holder assembly including a fixed plate mounted on said portion; guide rails secured beneath said fixed plate normal to said upper portion; a pair of side plates having spaced extended guide bars slidably engageable in said rails; a downwardly extending, rigid side form panel fixed to each of said side plates; said side form panels being perforated and shaped to engage in the waistband portion of a garment; porous covers secured to said form panels; and means for laterally adjusting the spacing of said form panels; spring clips mounted on each of said side plates and extending downwardly over said form panels to engage and retain a garment thereon; a rigid pleat presser pivotally mounted on each of said side plates to swing downwardly against the surfaces of said side form panels; said pleat presses being perforated and shaped to fit closely the surface of said form panels; and porous covers secured on said pleat presses; a toggle mechanism operatively connected to said pleat presses to lock the same in place against said form panels; a pair of downwardly extending leg elements secured to said fixed plate; said leg elements each comprising an imperforate fluid conducting pipe; a perforated fluid delivery pipe generally parallel thereto; a perforated jacket enclosing said conducting pipe and said delivery pipe; and a porous cover surrounding said jacket.
